CROSS-DRUM SUPERHEATER BOILER

Wilbur H. Armacost, New York, N. Y., assignor
to The Superheater Company, New York, N. Y.

Application January 21, 1933, Serial No. 652,807

3 Claims. (Cl. 122—478)

My invention relates to superheater boilers and more particularly to cross drum boilers having superheaters therein.

In order that my invention, together with its objects and advantages, may be fully and readily understood, I will now describe in detail and in connection with the accompanying drawing a low-head superheater boiler selected by way of example from a number of suitable embodiments of my invention. In the drawing:

Fig. 1 is a sectional elevation through a low-head superheater boiler taken on a plane perpendicular to the axes of the steam drums.

Fig. 2 is a sectional elevation taken on a line 2—2 of Fig. 1 looking in the direction of the arrows.

In the installation illustrated in the drawing, the water tube boiler 10 comprises a front drum 12, a rear drum 14 and a mud drum 16. Drums 12 and 16 are connected by a main generating bank composed of bent water tubes 18, 18. Upper drums 12 and 14 are connected by a group of circulators 20, 20 and drums 14 and 16 are connected by a bank composed of water tubes 22, 22. The banks composed of tubes 18 and 22 enclose, together with the circulators 20, a roughly triangular space 24 which is above the tubes 18 and below the circulators 20. Preferably baffling 26 is provided forming passes in the boiler so that the gases of combustion pass first upwardly and then downwardly through the space 24 before passing out through the bank composed of tubes 22 to the outlet 28. It will be understood that when the boiler 10 is heated a natural circulation occurs therein in the usual manner.

It will be seen that the vertical height between the drums 16 and 14 is relatively small compared to the horizontal distance between drums 14 and 12, drum 16 being almost directly below drum 14. It will be seen, therefore, that boiler 10 is of the low-head type. Such low-head boilers are installed in restricted spaces and are so compact that difficulty has been experienced in installing suitable superheaters therein. The great majority of low-head water tube boilers have been installed without superheaters although the tendency in other types of boilers has been to provide a superheater in almost every installation. The omission of superheaters from low-head boilers can not be attributed to the scarcity of such boilers since large numbers of them have been installed.

In accordance with my invention, I utilize the space 24, or a portion of it, for the superheater. It will be seen that, as appears clearly in Fig. 2,

the space 24 runs from side to side of the boiler and an opening 26 is made through side wall 28 registering roughly with the space 24 in that portion of such space in which the heating gases are apt to have a maximum temperature. As shown, moreover, parallel header chambers 30, 30 are placed just above the mouth of opening 26 and the drum 14 connected with one of the chambers 30 by a steam pipe 32. An off-take pipe 34 is provided for carrying away the superheated steam and is connected to the other header 30, pipes 32 and 34 preferably being connected to opposite ends of header chambers 30. It will be seen that the space available for the superheater is quite limited. Therefore, the problem of installing sufficient superheating surface in space 24 is a difficult one. I have illustrated a preferred arrangement wherein the superheater is composed of units 40, one of which is shown clearly in Fig. 2, and which facilitate the installation of a large amount of heating space per cubic foot of space occupied by the superheater. As illustrated, each unit 40 has two end or connecting portions 42, 42 each of which is formed of a single pipe length and connects to one of the header chambers 30. Intermediate the end portions 42, each unit 40 has an intermediate portion 44 one end of which connects to one portion 42 at a point 46a and the other end of which connects with the other end portion 42 at a point 46b. Preferably each unit 40 is so proportioned that the connecting points 46a and 46b fall within the opening in the side wall 28. However, I do not limit myself to this. Each intermediate portion 44 is formed of two parallel tube lengths 45a and 45b, the points 46a and 46b being points of bifurcation, as well as points of connection to the end portions 42. As appears in the drawing, the portions 42 of each unit 40 lie substantially in the same vertical plane and the points 46a and 46b lie one above the other close to the lower edge of the space 24 and opening 26. From the points 46a and 46b, the intermediate portion 44 of a given unit 40 extends laterally across the space 24 to near the other side wall of the boiler at which points the tubes 45a and 45b are turned back on themselves in bends 48 and 50 each at 180 degrees. From bends 48 and 50, the tubes 45a and 45b extend again toward the wall 28 and are joined approximately midway of the length of the steam path through the unit by a bend 52. Preferably the bend 52 lies within the opening 26 so that advantage can be taken of the height of the opening to make bend 52 one of large radius. It will be seen from 55

Fig. 1, moreover, that tubes 45a and 45b of a given unit 40 are set so that their centers at a given transverse plane are on lines considerably inclined to the vertical. Consequently, when a number of units such as 40 are arranged close together side by side the various tubes are given a staggered arrangement in a cross section of the superheater as appears in Fig. 1.

The connections between the end portions 42 and header chambers 30 serve to support the units at one end of each unit. Toward the other side of the boiler, I prefer to support the other ends of units 40 by a pair of hanger rods 54, 54 which extend downwardly from the roof of the boiler 10 through lanes in the circulators 20 to the level of the top row of tubes 18 where they are connected by a cross bar 56, on which the lower lengths of the tubes 45b rest. It will be seen that bar 56 extends parallel to tubes 18 and, in order to utilize the available space to best advantage, bar 56 lies in the passage for gases between two tubes 18 in the top row of such tubes. In order to stiffen the units 40 and hold the inner tube runs in the relative position shown, I prefer to insert spacer blocks in the units at points 58, 59 and 60 as best appears in Fig. 2. As also appears in Fig. 2, end portions 42 of each unit 40 extend from points 46a and 46b laterally beyond the edge of the opening 26 and thence upwardly to the chambers 30.

As appears clearly at 61, the units 40 are connected to header chambers 30 by joints of a known and readily breakable type. Preferably loose brick (not shown) are placed in the mouth of aperture 52 to screen joints 61 and chambers 30 from the hot gases. In order to prevent escape of gases through the opening 26 while permitting inspection, removal and replacement of units 40 with a maximum of convenience, I prefer to cover the mouth of opening 26 with a door plate 62 which is concave on its inner face and is hinged to a lower corner of one header chamber 30 as appears at 64. Plate 62 is so shaped that it falls by gravity against the face of the wall 28 and contacts therewith closely. Plate 62 has, however, a bumped or shield-like form providing room for the vertical parts of the end portions 42 where they lie beyond the mouth of the opening 26. As appears in dotted lines in Fig. 1, the plate 62 covers the header chambers 30 at their ends as well as at top, bottom and front. It will be seen that the arrangement in accordance with my invention provides a large amount of superheating surface in proportion to the space available for the superheater and that the form of unit disclosed herein is particularly well adapted to low-head boiler installations. Also, I have provided an arrangement whereby transverse units can be removed from and returned to a bent tube boiler with a minimum of difficulty.

While I have disclosed my invention as embodied in a low-head boiler, I do not limit my claims to such boilers.

What I claim is:

1. The combination of a boiler having two upper drums and one lower drum so arranged that the rear one of said upper drums is approxi-

mately above the lower drum and the two upper drums are nearly on the same level, groups of tubes connecting said drums and enclosing a roughly triangular space opening at the sides of the boiler, the one of said groups above said space having vertical lanes therethrough, a superheater having units extending into said space parallel to said drums, headers for said units at one end of said space to which said units are connected and from which they are partly supported, and supporting rods extending downwardly through the group between said upper drums for supporting the ends of said units at the ends opposite said headers, a side wall for the boiler having an opening therein registering roughly with a portion of the space for the superheater within the boiler and in which the superheater is composed of units each having two connecting portions extending out through said opening and a large radius return bend 20 lying in said opening in the side wall.

2. A unit for a superheater having two portions lying side by side and adapted to be connected to headers, a bifurcated portion having two tubes each connected at one end to one of said connecting portions and at the other end to the other of said connecting portions, said bifurcated portion having 180° bends at the end of the unit removed from said connecting portions whereby sections are provided lying above and parallel to sections connected to said end sections and 180° bends near the end of the unit adjacent said connecting portions for connecting the sections of the bifurcated portion, such bifurcated portion having its tubes offset horizontally when said connecting portions are vertical so that the individual tubes of the bifurcated portion of the given unit are arranged so close to a given vertical line as to obviate any substantial vertical lanes through the unit.

3. The combination of a boiler having vertically spaced tube banks and a superheater in the space between said banks and units extending transversely of the generating tubes, said units each having two portions lying side by side in a given vertical plane, two headers with which said portions connect, one to each, each of said units also having a bifurcated portion having two tubes connected at one end to one of said first mentioned portions and at the other end to the other of said first mentioned portions, said bifurcated portion having 180° bends at the end of the unit removed from said headers whereby sections are provided lying above and parallel to sections connected to said first mentioned portions and 180° bends near the end of the unit adjacent said headers for connecting the sections of the bifurcated portion, each of said bifurcated portions having its tubes lying close to and on opposite sides of a given vertical line, said superheater having a plurality of such units arranged so closely side by side that a tube bundle is formed having its tubes staggered with respect to gas flowing in the vertical direction and having no substantial vertical lanes therein.

WILBUR H. ARMACOST.
